FIBER CONTAINER WITH DUPLEX CLOSURE MEMBER

Ronald E. J. Nordquist, Maplewood, N. J., assignor to American Can Company, New York, N. Y., a corporation of New Jersey

Application April 28, 1949, Serial No. 90,202

5 Claims. (Cl. 229—7)

1

The present invention relates to containers for the packaging and delivery of liquids, such as milk and has particular reference to a sanitary fibre container having an improved duplex closure member construction including a binder sheet which protects and re-enforces the end member.

The invention constitutes an improvement upon the container illustrated and described in United States Patent 2,085,979 issued July 6, 1937 to John M. Hothersall on Container.

An object of the invention is the provision of a sanitary fibre container for milk and other liquids wherein fibre end members may be readily secured to tubular bodies in a simple lap joint and held in place by binder sheets which protect the end members against deterioration and damage such as splitting into loose laminations or softening of the fibre under exposure and adverse handling conditions.

Another object is the provision of such a container wherein the binder sheet re-enforces the end member and provides for the end member a smooth unbroken outer surface which will readily shed liquids and other foreign matter.

Another object is the provision of such a container which can be readily produced on existing machines and thereby is economical in cost of production.

Numerous other objects and advantages of the invention will be apparent as it is better understood from the following description, which, taken in connection with the accompanying drawings, discloses a preferred embodiment thereof.

Referring to the drawings:

Figure 1 is a perspective view of the top end of a container embodying the instant invention, the view illustrating a plug closure secured to the container and in open position;

Fig. 2 is an enlarged sectional view taken substantially along a plane indicated by the lines 2—2 in Fig. 1, with parts broken away and with the plug closure in closed position;

Fig. 3 is a greatly enlarged sectional view of that portion of Fig. 2 shown at the left of the figure, with parts broken away;

Fig. 4 is a perspective view of the top end of the container shown in Fig. 1, with the plug closure closed and the entire top of the container covered with an overcap;

Fig. 5 is an enlarged sectional view taken substantially along a plane indicated by the lines 5—5 in Fig. 4, with parts broken away; and

Fig. 6 is a view similar to Fig. 4 and showing

2

the plug closure and a portion of the overcap in raised and open position.

As a preferred or exemplary embodiment of the instant invention the drawings disclose the upper end of a fibre container comprising a substantially rectangular tubular body 11 (Figs. 1, 2 and 3) closed at its top end with a duplex closure member 12. The bottom end of the body 11 may be closed with the same type of duplex closure member 12 or may be closed with any other type of closure member, such as for example the construction shown in the above mentioned Hothersall patent.

The body 11 preferably is formed from a single sheet of fibrous material folded at right angles to provide four side walls 15, the short edges of the sheet being overlapped in a vertical lap side seam 16. The marginal edges of the seam preferably are secured with a suitable adhesive so that a liquid tight side seam results.

Adjacent the top end of the body 11 which is closed by the duplex closure member 12, the marginal end portions of the body are bent obliquely inwardly as at 18 and thence upwardly in a short vertical neck section 19. At the upper end of the neck section 19, the marginal end portions of the body extend outwardly and thence upwardly and inwardly in a substantially horizontal overhanging peripheral hem or double thickness flange 21. The inner adjacent faces of the flange preferably are adhesively secured together permanently with a suitable liquid proof adhesive 22 (Fig. 3). This flange provides a solid seat for the duplex closure member 12.

The duplex closure member 12 includes an end member or disc 25 and a binder sheet 26. The end member 25 preferably is flat and of a size sufficient to cover the entire end of the body, the outer marginal edge portions of the end member overlapping and being substantially coextensive with the top of the flange 21 and being permanently secured thereto with a suitable waterproof adhesive 27 (Fig. 3). The outer or peripheral edges 28 of the end member 25 preferably terminate adjacent or in vertical alignment with the outer peripheral edges of the flange 21. This end member is made of relatively thick fibre board, preferably of multi-ply or laminated construction to impart strength and rigidity. It may also be formed of single-ply relatively thick stock.

The binder sheet 26 is of relatively thinner stock and is utilized to re-enforce and hold the end member 25 in place and to protect its outer surface and especially its exposed peripheral edges 28 against separating or splitting into loose

layers or laminations under exposure and adverse handling conditions when the end member 25 is made from multi-ply stock and also to protect the same when made from single-ply comparatively thick stock. For this purpose the binder sheet 26 preferably is made of a relatively thin, tough and strong, tightly pressed fibre material. This binder sheet extends over the entire outer surface of the end member 25 and is permanently secured thereto by a film of a suitable waterproof adhesive 29 (Fig. 3).

The binder sheet 26 is of larger dimensions than the end member 25, having marginally extending edge portions 30 which are wide enough to extend downwardly against and are adhesively secured to the outer peripheral edges 28 of the end member 25 and the adjacent outer peripheral edges of the flange 21, and wide enough to project under and being adhesively secured to the lower outer surface of the flange 21 as best shown in Fig. 3. In this manner the binder sheet locks and retains the end member in place and protects it against damage as mentioned above, and at the same time provides for the container a smooth flat top, free from any crevices or indentations so that surface liquids or other foreign matter will be prevented from collecting on the top of the container.

The duplex closure member 12 preferably is provided with a dispensing opening 32 (Figs. 2 and 3) formed in the duplex closure member 12 adjacent one of its corners. The binder sheet 26 also has an opening in alignment with the dispensing opening. This dispensing opening 32 preferably is surrounded by a protecting and reinforcing barrier comprising a flat barrier member 33 of relatively thick fibrous material permanently secured by suitable waterproof adhesive 34 (Fig. 3) to the outside surface of the binder sheet 26. The barrier member is formed with an opening 35 (Fig. 1) which registers with the dispensing opening 32. The outer edges of the barrier member 33 adjacent the outer edges of the duplex closure member 12 preferably coincide with the edges of the closure member. Inwardly of the edges of the closure member, the edges of the barrier member form a stepped barrier which deflects surface water or other foreign matter, away from the dispensing openings 32, 35.

A friction plug closure element 37 is provided for closing and reclosing the dispensing openings 32, 35. This closure element 37 extends over the top surface of the barrier member 33 to maintain it free from contamination and is hingedly secured thereto by a wire staple 38 disposed adjacent the inner barrier edge of the member 33.

In some cases it may be desirable to protect the entire top of the container including the friction plug closure element 37. For this purpose an overcap 40 (Figs. 4, 5, and 6) may be applied over the duplex closure member 12. In the form of overcap disclosed in the drawings, the triangular portion opposite the friction plug closure element 37 is permanently secured by a suitable waterproof adhesive, to the outer surface of the binder sheet 26, the outer peripheral edges of the overcap terminating adjacent the outer peripheral edges of the duplex closure member 12 as best shown in Fig. 5.

The triangular portion of the overcap 40, that overlaps the friction plug closure element 37 is formed with a hinge crease 39 which connects this portion to the opposite secured triangular portion of the overcap and is free from the binder sheet 26. This free triangular portion of the

overcap is provided with an overhanging marginal edge portion 41 which extends down over and around the combined outer peripheral edges of the plug closure element 31, the barrier member 33, and the duplex closure member 12, and is crimped in place under the flange 21, as best shown in Fig. 5 when the free portion of the overcap is in protecting position as shown in Fig. 4. When it is desired to open the container, the free portion of the overcap 40 may be readily lifted and access obtained to the plug closure 31 as shown in Fig. 6.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container for liquids comprising a tubular fibre body, a flange extending outwardly around one end of said body, a relatively thick end member of laminated material supported on said flange with its peripheral edges in substantial alignment and coextensive with the outer periphery of said flange and having its marginal edge portions adhesively secured to said flange, said end member having a dispensing opening, a relatively thin and strong binder sheet of larger dimensions than said end member disposed outside of said end member and adhesively secured thereto, the marginal edge portions of said binder sheet overlying and being adhesively secured to the peripheral edges of said end member and flange and to the under surface of said flange, said binder sheet also having a dispensing opening in alignment with the dispensing opening of said end member, said binder sheet being thus permanently bonded to said end member and to said flange for holding said end member in place and for protecting it against splitting into loose laminations under exposure and adverse handling conditions, and a closure element mounted on said binder sheet for closing its dispenser opening and the dispenser opening of said end member.

2. A container for liquids comprising a tubular fibre body, a double thickness folded flange formed on said body at an end thereof and projecting outwardly from said body with the raw edge of the flange disposed inwardly thereof, a relatively thick fibre end member supported on said flange with its peripheral edges in substantial alignment with the outer and folded periphery of said flange, the marginal edge portions of said end member being adhesively secured to said flange, said end member having a dispensing opening, a relatively thin binder sheet of larger dimensions than said end member extending over the entire area of the outer surface of said end member and having a dispensing opening in alignment with the dispensing opening of said end member, said binder sheet being adhesively secured to and having marginal edge portions projecting beyond said end member and also overlying and adhesively secured to the substantially aligned peripheral edges of said end member and flange and to the exposed under surface of said flange for holding said end member in place and for protecting it against deterioration and damage under exposure and adverse handling conditions, and a friction plug closure

mounted on said end member and having frictional engagement within said dispensing openings for sealing said container.

3. A container for liquids comprising a tubular fibre body, a flange extending around one end of said body, a flat and relatively thick fibre end member supported on said flange and having its marginal edge portions adhesively secured to said flange, a relatively thin binder sheet of larger dimensions than said end member extending over the entire area of the outer surface of said end member and adhesively secured thereto, said binder sheet having marginal edge portions projecting beyond said end member and extending over the outer peripheries of said end member and flange and adhesively secured thereto, the terminal edge of said binder sheet portions being adhesively secured to the under face of said flange, said end member and said binder sheet having aligned dispensing openings therein, a barrier member disposed on top of said binder sheet and adhesively secured thereto and having an edge thereof terminating adjacent the edge of said end member and forming a barrier around said dispensing opening for excluding therefrom surface liquids which may collect on said binder sheet, said barrier member having a dispensing opening disposed in alignment with said other dispensing openings, and a friction plug closure element hingedly connected to said barrier member for closing the dispensing openings in said barrier member, said binder sheet, and said end member.

4. A container for liquids comprising a tubular fibre body, a flange extending around one end of said body, a flat and relatively thick fibre end member supported on said flange with its peripheral edges in substantial coextension and alignment with the outer periphery of said flange and having its marginal edge portions adhesively secured to said flange, a relatively thin binder sheet of larger dimensions than said end member extending over the entire area of the outer surface of said end member and adhesively secured thereto and having its marginal edge portions extending over and adhesively secured to the outer peripheries of said end member and said flange the terminal edge of said marginal edge portions being adhesively secured to the

under face of said flange, said end member and said binder sheet having aligned dispensing openings therein, a friction plug closure element for closing the dispensing openings in said binder sheet and said end member, and an overcap of substantially the same area and shape of the top as said end member overlying said binder sheet and said closure element, said overcap having a portion opposite said closure element adhesively attached to said binder sheet and having an unattached hingeable portion overlying said closure element, said unattached portion having a marginal edge portion extending beyond said end member and crimped under said flange to hold it in place.

5. A container for liquids comprising a tubular fibre body, a flange extending outwardly around an end of said body, a relatively thick and substantially flat fiber end member supported on said flange with its peripheral edges substantially in alignment and coextensive with the periphery of said flange and having its marginal edge portions adhesively secured to said flange, a relatively thin binder sheet of larger dimensions than said end member disposed outside of said end member and adhesively secured thereto, the marginal edge portions of said binder sheet overlying and being adhesively secured to the peripheral edges of said end member and the under surface of said flange, said binder sheet being thus permanently bonded to said end member and to said flange for holding said end member in place and for protecting it against deterioration and damage under exposure and adverse handling conditions.
